UNITED STATES PATENT OFFICE

HENRY D. SCOTT, OF WHEELING, WEST VIRGINIA

THREAD PROTECTOR

Application filed March 28, 1929. Serial No. 350,652.

This invention relates to a thread protector for internally threaded pipe ends, couplings, and the like, and has for its object the provision of a simply constructed inexpensive protector which may be readily and securely attached to the end of a pipe or coupling to prevent injury to the thread thereof when it is being handled or is in transit.

- 10 An embodiment of the invention is illustrated in the accompanying drawings of which Fig. 1 is a plan view of a disk out of which the protector is formed; Fig. 2 a view similar to Fig. 1 showing the protector in a further stage of its manufacture; Fig. 3 a perspective view of the complete protector; and Fig. 4 a central cross sectional view of the protector and the end of a pipe coupling in which the protector is arranged.
- 20 The protector provided according to this invention is formed from a metal disk having a diameter substantially equal to the outer diameter of a coupling with which it is adapted to be employed. From the center of the disk a plurality of tongues, preferably two, are struck and bent downwardly at right angles to the plane of the disk, and are then preferably pressed to arcuate shape conforming to that of the inner wall of a pipe or coupling. For securing the protector in place, threads are formed on the outer faces of the tongues for engaging the internal threads of the coupling.
- 30 Referring now to the drawing, the invention is illustrated in a simple form as comprising a metal disk 1, from the central portion of which a pair of tongues 2 and 3 are formed by slitting the disk in the manner indicated in Fig. 1 and then pressing the portions between the slots downwardly and outwardly to positions at right angles to the plane of the disk, and opposite to each other. In addition to being forced downwardly, the tongues are preferably pressed to arcuate shape conforming to the inner walls of a coupling, and have threads 4 formed on their outer faces for screwing the protector into a coupling, such as that illustrated at 5 in Fig. 4.

- 50 The disk, as stated above, is preferably

made with a diameter which is substantially the same as the outside diameter of a coupling to which it is adapted to be attached, or at least a diameter sufficient to adequately protect the end of the coupling from being 55 jammed or injured when the protector is in place. To position the protector in the end of a coupling, tongues 2 and 3 are inserted in the end thereof and the protector rotated until disk 1 abuts against the outer end of 60 the coupling, as illustrated in Fig. 4.

The simplicity and economy of construction, as well as the adequate protection afforded by the protector, will be readily appreciated by those skilled in the art. The 65 protector may be made in various sizes, and may be used repeatedly. Although it covers only a portion of an internal thread of a pipe or coupling, nevertheless the protector so firmly grips the thread, and its peripheral 70 margin so protects the end of a pipe or coupling that the thread as a whole is adequately protected.

According to the provisions of the patent statutes, I have explained the principle and operation of my invention, and have illustrated and described what I now consider to represent its best embodiment. However, I desire to have it understood that, within the scope of the appended claims, the invention 80 may be practised otherwise than as specifically illustrated and described.

I claim as my invention:

1. A thread protector for internally threaded pipe couplings and the like, comprising a disk having a plurality of tongues bent downwardly from the plane thereof and provided with threads on their outer faces for engaging the internal threads of a pipe or coupling, the disk having an annular marginal portion for protecting the end of the pipe or coupling.

2. A thread protector for internally threaded pipe couplings and the like, comprising a metal disk having a plurality of tongues struck out of the center thereof and bent downwardly at right angles thereto, said tongues being provided with threads on their outer faces for engaging the threads of a pipe or coupling, and said disk having an 100

annular marginal portion for protecting the end of the pipe or coupling.

3. A thread protector for internally threaded pipe couplings and the like, comprising a metal disk having a pair of tongues struck out of the center thereof and bent downwardly at right angles thereto and opposite to each other, the outer faces of said tongues being provided with threads for engaging the threads of a pipe or coupling, and the disk having an annular marginal portion for protecting the end of a pipe or coupling.

In testimony whereof, I sign my name.

HENRY D. SCOTT.
